New York, N. Y., a corporation of Virginia

Application April 24, 1937, Serial No. 138,675

13 Claims. (Cl. 101—157)

The present invention relates to improvements in intaglio presses of the type adjustable for printing from cylinders of different diameters.

An object of my invention is to provide a printing press in which the printing point is maintained constant and the printing cylinder bearings are correspondingly adjustable for cylinders of different diameters. Obviously, the fountain bowl must also be shifted for printing cylinders of different sizes but other changes of parts, including the troublesome adjustments of compensators heretofore necessary, are avoided.

Another object of my invention is to provide a housing for the printing cylinder and fountain bowl. This is of importance when printing at high speed with highly volatile ink, as is now customary, because the housing prevents undue drying out of the ink.

Another important feature of my invention lies in the setting of the doctor blade close to the printing point so that a change in printing cylinder diameter will involve only a slight change in position of said blade. By positioning the blade close to the printing point, drying of the highly volatile ink on the cylinder before it is picked up by the web, is prevented.

Other objects and advantages of my invention will appear in the following description of a preferred embodiment and thereafter the novelty and scope of the invention will be pointed out in the claims.

In the accompanying drawings:

Figure 1 is a view in end elevation of a printing couple embodying my invention, the parts being adjusted for a large size printing cylinder;

Fig. 2 is a front elevation of the couple looking from the right hand side of Fig. 1, with certain parts shown in section;

Fig. 3 is a view in section taken substantially on the line 3—3 of Fig. 2 but showing the parts adjusted for a small size printing cylinder;

Fig. 4 is a view in section taken on line 4—4 of Fig. 2; and

Fig. 5 is a fragmental end view showing one of the vertically adjustable blocks which provide bearings for the journal boxes of the printing cylinders.

The printing unit illustrated in the drawings is adjustable for printing cylinders of two sizes, one being just twice the diameter of the other. It will be understood that a printing press may comprise a number of such units or couples disposed in tandem.

The printing unit comprises a base 10 to which are bolted a pair of side frames 11. At their

upper ends the frames 11 are bolted to beams 13 which connect the unit illustrated to other units and other parts of the press. The web W enters the printing unit or couple from a preceding printing couple or directly from a paper roll, passing first about a water cylinder 15 which is adapted to cool the web if it has been heated by the steam drum of a preceding printing unit. The web then passes about a compensator roll 16 and over a bar 17 and enters between a rubber faced impression cylinder 18 and a printing cylinder 20 or 20A, as the case may be. From the printing cylinder the printed web passes about a bending roll 22 and over a steam drum 23. Thence it is guided by suitable means (not shown) to the next couple of the press or directly to the folder.

The cylinder 18 is pressed against the printing cylinder by a pressure roll 24. The impression cylinder 18 is journaled in blocks 27 which have limited vertical sliding movement in the slide blocks 26. To prevent overheating when running at high speed, the pressure roll may be water cooled, and, to this end, provision is made for circulating water through the roll by way of pipes 28 which pass through stuffing boxes 29. It will be understood that the water cylinder 15 is similarly cooled, being provided with water pipe connections which pass through suitable stuffing boxes.

The pressure roll 24 and impression cylinder 18 are friction driven by the printing cylinder 20, and provision is made for adjusting the blocks 26 so as to vary the pressure of the cylinder 18 on the printing cylinder and also to raise the impression cylinder clear of the printing cylinder, when changing printing cylinders or when threading the web through the couple. To this end screws 32 are provided which rise from the top of the slide blocks 26 respectively. Each screw 32 is threaded through a nut 33 pivoted to one end of an arm 34. Each arm 34 is pivoted, as at 35, to the adjacent side frame 11 and is held more or less rigid by the pressure of a heavy spring 36 at the opposite end thereof. The screws 32 are attached to the slide blocks 26 with swivel connections so that they may be rotated to raise or lower the slide blocks with respect to the arms 34. Fixed to the upper end of each screw 32 is a bevel gear 38 (Fig. 2) which meshes with a bevel pinion 39. The bevel pinions 39 are fixed upon a shaft 40, and this shaft is provided at one end with a hand wheel 41, whereby it may be manually operated to turn the screws 32.

30

35

35

40

45

45

50

50

55

A power means is also provided for turning shaft 40 when desired. Rotatably mounted on shaft 40 is a worm gear 43 which meshes with a worm 44 fixed on a shaft 45. The latter is journaled in a housing 46 which is pivoted on the shaft 40 and encloses said worm and worm gear. A plate 30 outside this housing is integrally connected to the worm gear 43 and is formed with an annular series of holes 31a, any one of which may be engaged by a spring seated lock pin 31 in the hand wheel 41. By this means the worm gear 43 may be locked to the hand wheel and hence to shaft 40. A motor bracket 48 (Fig. 1) projects from the housing 46 and is provided at its outer end with a pivot slot 49 to receive a stud 50 projecting from the adjacent press frame 11. A reversible motor 51 is mounted on this bracket and a suitable coupling 52 connects the motor shaft to the worm shaft 45. The motor bracket pivots on the stud 50 as the shaft 40 is raised or lowered by adjustment of the screws 32.

The shaft 40 may be turned manually when the pin 31 is disengaged from plate 30 or may be turned by the motor 51 when the pin engages any of the holes 31a. Rotation of the shaft in one direction will turn the screws 32 in such direction as to raise the slide blocks 26 and with them the pressure roll 24 and impression cylinder 18. Turning of the shaft in the opposite direction will lower the impression cylinder and cause the pressure roll to bear against the printing cylinder. Further rotation of the shaft 40 in lowering direction will result in applying pressure of the springs 36 on the pressure roll which, in turn, will press the impression cylinder 18 against the printing cylinder 20.

The printing cylinder turns in cylinder boxes 56 which rest in bored recesses 57 formed in slide blocks 58 disposed respectively at opposite ends 40 of the cylinder. The blocks 58 are mounted to slide in suitable ways 59 formed in the press frame 11. Each block is raised and lowered by a screw 60 threaded into a nut 61 carried by the block. Each screw has a worm gear 62 fixed thereto. The worm gears are engaged by worms 63 fixed upon a shaft 64. The latter is provided at one end with a hand wheel 65, so that by turning this hand wheel the screws 60 will be rotated and the blocks 58 will be raised or lowered as the case may be. The frames 11 are provided with sockets 66 to receive the nuts 61 when the blocks 58 are lowered.

In Fig. 1, I show a large printing cylinder 20 mounted in operating position, and in Fig. 3, a small printing cylinder 20A in printing position. The printing point which is the line of contact of the web with the top of the printing cylinder, remains fixed, and consequently the blocks 58 must be lowered to mount the cylinder 20 and must be raised to mount the cylinder 20A. When the blocks 58 are lowered to the position shown in Fig. 1 they may be locked against the side frames 11 by bolts 53 which are screwed into tapped holes 67 in the blocks, but when the blocks are raised 65 to mount the small cylinder 20A the bolts 53 are threaded into other tapped holes 68 in said blocks. When the blocks are in raised position they project so far out of the ways 59 that the bolts may not suffice to hold them firmly in place, and hence I provide a clamping jaw 69 on each side frame 11, as shown in Fig. 5. This jaw enters a recess 70 formed at the top of the adjacent block 58 and by tightening up a bolt 71 the top of the block is firmly clamped to the press frame.

The printing cylinders are inked by dipping into

a fountain bowl 72 and obviously this bowl must be raised for a small cylinder 20A, and lowered for the larger cylinder 20. The fountain bowl is formed at each end with a shoulder 73 which rests upon a ledge 74 formed on an arm 75. The arms 75 are secured to vertical bars 76 which are provided adjacent their upper ends with teeth 77, as shown in Fig. 3. These teeth are engaged by pinions 78 fixed upon a shaft 79 extending from end to end of the couple and journaled in the side frames 11. At one end of the shaft 79 a worm gear 80 is fixed, as shown in Fig. 1, and this gear is engaged by a worm 81 on a worm shaft 82 which is provided with a hand wheel 83. By operating this hand wheel the arms 75 will be raised and lowered, as desired, to adjust the position of the fountain bowl.

As shown particularly in Fig. 3, a doctor blade 85 is mounted close to the printing point and by comparing the position of the doctor blade in Fig. 3 with that in Fig. 1 it will be observed that a very slight adjustment is required to adapt the blade for different sizes of cylinders. It will also be noted that the angular distance between the printing point and the point of contact of the doctor blade with the printing cylinder is comparatively small, so that there is little opportunity for the ink on the cylinder to dry before it is picked up by the web W.

The doctor blade 85 is clamped in a holder 86 which is pivoted upon a slide block 87 adapted to slide on a rail 88 extending from end to end of the couple. In order to provide for the adjustment from the position shown in Fig. 1 to that shown in Fig. 3, or, vice versa, the rail 88 is slidably fitted to blocks 89 which are fixed to the press frame 11. While the rail is slidable laterally on said blocks, it is prevented from moving endwise by a central bracket 95 fastened to the bottom of the rail, as shown in Fig. 3. This bracket is slotted lengthwise to receive a shoulder screw 100 threaded into a brace 101 connecting the opposite press frames 11. The adjustment of the doctor blade is effected by operating a crank 90 at each end of the couple. Each crank 90 is fixed upon a screw 91 which passes through a poppet 92 fixed to the adjacent frame 11 and which is maintained against endwise displacement by collars 93 fixed on the screw and bearing against opposite faces of the poppet 92. Each screw is threaded through a poppet 94 fixed upon rail 88 so that by turning the crank 90 the rail 88 is adjusted laterally toward or from the printing point. The slide block 87 is reciprocated on the rail by means which will be described hereinafter. Pressure of the doctor blade 85 on the printing cylinder is maintained in the usual manner, by a weight 96 attached to a chain 97 which passes over a sheave 98 and is fastened to an arm 99 fixed to the holder 86.

A housing 102 encloses the printing cylinder and the fountain bowl, as shown to best advantage in Fig. 3. This housing is provided at the front with a pair of doors 103 and 104 which are hinged respectively at the top and bottom of the housing. In order to permit of changing printing cylinders, the side wall of the housing 102 is formed with openings 105 extending inwardly from the front of the housing, and each opening is normally closed by a sliding door 106. Each door is formed with a double lip 107 at the top and bottom to receive, respectively, the upper and lower edges of the opening 105. At its inner end each opening is formed with a pair of half-round cutouts 108 and 109 respectively, to clear

the printing cylinder shafts. When the large printing cylinder 20 is mounted in the couple, as shown in Fig. 1, the shaft of this cylinder passes through the lower cutouts 109. The sliding doors 106 are each formed with a cooperating half-round cutout 110 to fit about the outer side of the cylinder shaft. To close the cutouts 108 when the large printing cylinder is mounted in the couple, a projecting cover plate 111 is provided 10 on each of the doors 106. When the smaller printing cylinder 20A is mounted in place, as shown in Fig. 3, the shaft of this cylinder passes through the upper cutouts 108. The sliding doors 106 are then inverted so that the cutouts 110 will register with cutouts 108 to fit about 15 said shaft, and the cover plates 111 will then close the openings 109.

The housing 102 which rises above the printing point has an opening at the top to admit the web W and the pressure roll 18, as well as the doctor blade and operating mechanism therefor. However, there is a baffle plate 112 depending from the rail 88 and another baffle plate 113 fixed to the doctor blade holder 86 which in large measure shield the printing cylinder from exposure to a drying atmosphere. These baffles serve to catch the ink that is scraped from the printing cylinder by the doctor blade and any ink spray that may be thrown off centrifugally from the printing cylinder, and cause such ink to flow back into the fountain bowl. The fountain bowl is supplied with ink through an inlet 115 which may be suitably connected by a flexible pipe to a pump. Surplus ink overflows the rolled edge 116 30 at the rear of the fountain and drops to the bottom of the housing 102. Thence it passes out through a drain pipe 118.

Referring now to Figs. 2 and 4, it will be seen that the printing cylinder is driven by a main shaft 120 which extends lengthwise of the press and is journaled in suitable bearings 121 supported on pedestals 122. The shaft passes through a gear box 123 and has a worm 124 fixed thereon within said box. This worm drives two worm gears 125 and 126. The worm gear 125 is just half the diameter of the worm gear 126, and consequently the shaft 127 to which the worm gear 125 is fixed, will be driven at twice the speed of the shaft 128 to which the worm gear 126 is secured. As will be explained later 40 the shaft 127 is arranged to drive the smaller printing cylinder 20A, while the shaft 128 drives the larger printing cylinder 20 at half the rotational speed of cylinder 20A, but the surface speed of these cylinders will be the same.

Fixed upon the shaft 127 is a worm 130 which drives a worm wheel 131. The latter is mounted on a shaft 132 (Fig. 4) which projects from the housing 123 and has at its outer extremity a crank 134. This crank is connected by a link 135 to a pin 136 connecting the lower ends of a pair of bell crank levers 137 mounted on a shaft 138. The upper ends of these levers are connected by a pin 139 which forms a bearing for a link 140 50 that is connected to the doctor blade slide block 87. By this means said block is reciprocated causing a corresponding reciprocation of the doctor blade attached thereto. The link 140 is slidable on the pin 139 to provide for variations in adjustment of the rail 88.

The shaft 127 is suitably supported in journals in the housing 123 and projects through the housing on the press side, i. e., the left side, as viewed in Fig. 2. Fixed upon this projecting 75 part of the shaft is a transversely slotted hub 142.

The shaft 128 is operatively connected by gears 143 and 144 of equal diameter to a shaft 145 which projects from the press side of the housing 123 and has a slotted hub 146 fixed thereon. Hubs 142 and 146 are of the same dimensions and each is adapted for engagement with a dog 147. In Fig. 2, this dog is bolted to the hub 146 with a transverse rib thereon seated in the slot of said hub. The dog 147 is forked, having lugs 148 which engage slots formed in a split clutch member 149 clamped upon the adjacent end of the printing cylinder shaft. Thus, a driving connection is provided for the large cylinder 20. When the smaller cylinder 20A is used the clutch member 149 is secured to the shaft of said cylinder and the forked dog 147 is fastened to the hub 142. Since the gearing is such that the peripheral speed of the two printing cylinders will be the same there will be no change in speed of the web W and other friction driven parts. 20

To provide for axial adjustment of the cylinders a bracket 150 is secured to the block 58 on the end remote from the driving gear. This bracket carries a nut 151 through which a feed screw 152 may be screwed by operating a hand wheel 153 on the outer end of the screw. The screw 152 has a swivel connection to a fitting 155 which is bolted on the adjacent end of the printing cylinder shaft. The swivel connection permits the screw 152 to turn freely but prevents axial movement of the screw with respect to the fitting 155. By this means the printing cylinder may be adjusted axially, as necessary, to obtain a proper printing register.

The steam drum 23 is mounted in suitable bearings 160 formed in brackets 161 mounted on the overhead beams 13. The drum is fitted with a steam inlet pipe 162 and an outlet pipe 163, and these pipes pass through suitable stuffing boxes, as indicated at 164. The steam drum is positively driven by the impression cylinder 24. To this end a sprocket wheel 166 is fixed upon the shaft of the pressure roll, and a sprocket chain 167 provides a driving connection between sprocket wheel 166 and a sprocket wheel 168 35 fixed upon a shaft 169. The latter has a pinion 170 fixed thereto which meshes with a gear 171 fixed upon the steam drum 23. The sprocket chain 167 is passed about a pair of idlers 172 and 173, so that vertical adjustment of the pressure 40 roll will not cause any substantial variation in tautness of the sprocket chain 167. The idler 172 is fixed while the idler 173 is spring seated.

The operation of adjusting the printing couple for cylinders of different sizes will be now illustrated by reviewing the steps necessary to replace the printing cylinder 20 with the printing cylinder 20A. It will be understood that the sequence of these steps may be varied. The doctor blade is first raised by depressing the arm 89 55 and is held in this position by means of a latch 175. The pressure roll blocks 26 are raised by turning the shaft 48 manually, or by means of the motor 51, so as to relieve pressure on the cylinder 20. The fitting 155 is unclamped from 60 one end of the cylinder shaft and the coupling 149 is unclamped from the opposite end of said shaft. The doors 103 and 104 of the housing 102 are then swung open in which position they are held by springs 176 and 177 respectively, as 65 said springs are carried past dead center. The sliding doors 109 are drawn out of their positions in the side walls of the housing and the cylinder 20 then may be removed through the front of the housing. Preferably, the fountain bowl 72 70 75

- is removed from its supports before the cylinder is withdrawn. The dog 147 may now be unfastened from the lower hub 146 and secured to the upper hub 142. The slide blocks 58 may then be 5 raised to their proper position by operating hand wheel 65 and be secured by means of the bolts 53 and clamps 69, after which the smaller cylinder 20A may be mounted in place with its journal boxes supported in said slide blocks. 10 The fountain bowl support is then raised by operating the hand wheel 83 and the fountain bowl is placed in position on its supports. The sliding doors 106 are now inverted and reintroduced to close the openings 105 with the cover 15 plates 111 in position to close the lower cut-outs 109 in the side walls of the housing. The doors 103 and 104 may then be closed. The fitting 155 may now be clamped upon the shaft of the printing cylinder 20A and the coupling member 149 will be clamped upon the opposite end of said shaft in engagement with the dog 147. No other adjustments will be necessary to effect a change from a large to a small cylinder, and the change from the small to the large cylinder 25 will involve a similar series of steps which need not be specifically set forth.

In this particular embodiment of my invention provision is made for only two printing cylinders, one being just twice the diameter of 30 the other, but my invention is not limited to such relative sizes of cylinders. Thus, while I have described a preferred embodiment of my invention, it will be understood that this is to be taken as illustrative and not limitative, and 35 that I reserve the right to make various changes in form, construction, and arrangement of parts, without departing from the spirit and scope of my invention as set forth in the following claims.

I claim:

- 40 1. A printing couple adapted to include, interchangeably, printing cylinders of different diameters, in combination with a frame, printing cylinder bearings adjustably mounted on the frame, means for adjusting said bearings to compensate for the different cylinder diameters and bring each cylinder to the same printing point, an ink fountain into which the printing cylinder extends to be inked, means for adjusting the fountain to accommodate the printing cylinders of different diameters, and means for driving the printing cylinder adjustable to compensate for the different cylinder diameters and give each of said different sized cylinders the same surface speed.
- 45 55 2. A printing couple including, interchangeably, printing cylinders of different diameters, an ink fountain into which the printing cylinder extends to be inked, means for adjusting the fountain to accommodate the printing cylinders of different diameters, a frame, a pair of supports mounted to slide on the frame, a pressure roll mounted in said supports, a pair of slide blocks slidable on the frame and providing bearings in which the printing cylinders may be 60 mounted, means for adjusting said blocks to compensate for the different cylinder diameters so that each printing cylinder may be brought to the same printing point, means for adjusting said supports to vary the pressure of said pressure roll transmitted to the printing cylinder, means for driving the printing cylinder adjustable to compensate for different sizes of printing cylinders so as to give each cylinder the same surface speed, and means for guiding the web 65 between the printing cylinder and pressure roll.

3. In a web press, a printing couple adapted to include, interchangeably, printing cylinders of different diameters, a frame, means supported by the frame for guiding a web to a fixed printing level, an ink fountain into which the printing cylinder extends to be inked, means for adjusting the fountain to accommodate the printing cylinders of different diameters, slide blocks manually adjustable on the frame toward and from said printing level, said blocks providing 10 bearings in which the printing cylinders may be interchangeably mounted, manual means for adjusting said blocks to compensate for the different printing cylinder diameters, said web guiding means including means for pressing the 15 web against the printing cylinder at said printing level, and means for adjusting the pressure of the web against the printing cylinder.

4. In an intaglio printing press, a printing couple adapted to include, interchangeably, 20 printing cylinders of different diameters, a frame, bearing blocks mounted to slide on the frame and providing bearings in which the printing cylinders may be interchangeably mounted, means for adjusting said bearings to compensate 25 for the different printing cylinder diameters so as to bring each cylinder to the same printing point, a doctor blade adapted to engage the printing cylinder immediately adjacent said printing point, and means for adjusting said blade to compensate for the different printing cylinder 30 diameters.

5. In an intaglio printing press, a printing couple adapted to include, interchangeably, printing cylinders of different diameters, a 35 frame, bearing blocks mounted to slide on the frame and providing bearings in which the printing cylinders may be interchangeably mounted, means for adjusting said bearings to compensate for the different printing cylinder diameters so as to bring each cylinder to the same printing point, a doctor blade adapted to engage the printing cylinder immediately adjacent said printing point, and means for adjusting said blade toward and from the printing point to 40 compensate for the different printing cylinder 45 diameters.

6. In an intaglio printing press, a printing couple adapted to include, interchangeably, printing cylinders of different diameters, a frame, 50 bearings slidable vertically on the frame to mount said printing cylinders interchangeably, means for adjusting said bearings to compensate for the different printing cylinder diameters so as to bring each cylinder to the same printing point, a doctor blade adapted to engage the printing cylinder immediately adjacent said printing point, a mounting for said blade adjustable horizontally on the frame, and means for adjusting said mounting to compensate for different printing cylinder 55 diameters.

7. In a printing press, a printing couple adapted to include either of a pair of printing cylinders, one cylinder being twice the diameter of the other, a frame, blocks slidable vertically on 65 the frame and providing bearings for either of said printing cylinders, means for adjusting said bearings to compensate for the difference in diameter of the cylinders so as to maintain a common printing level for both cylinders, a driving gear provided with two driving elements, one a high speed element and the other a slow speed element, one driven at double the speed of the other, and means for coupling the cylinder of larger diameter to the slow speed element and 70 75

the small cylinder to the high speed element so as to maintain the same printing speed with either of said cylinders.

8. In an intaglio printing press, a printing couple adapted to include either of a pair of printing cylinders, one cylinder having twice the diameter of the other, a frame, blocks slideable vertically on the frame and providing bearings for either of said cylinders, means for adjusting said bearings to bring the printing cylinder to a fixed printing point to compensate for the difference in diameter of the cylinders so as to maintain a common printing point for both cylinders, a driving gear provided with two driving elements, one driven at double the speed of the other, means for coupling the large cylinder to the slow speed element or the small cylinder to the high speed element so as to maintain the same printing speed with either of said cylinders, and a doctor blade adapted to engage the printing cylinder adjacent said printing point, means operated by said driving gear for reciprocating the doctor blade, and means for adjusting the doctor blade toward and from said printing point to compensate for the difference in diameter of the printing cylinders.

9. In an intaglio printing press, a printing couple adapted to include either of two printing cylinders of different diameters, a frame, printing cylinder bearings mounted on the frame and adjustable in vertical planes, means for effecting such adjustment of the bearings whereby each of said cylinders may be adjusted to the same printing level, a fountain bowl into which either of said cylinders extends to be inked, means for adjusting the fountain bowl vertically, and a housing enclosing the printing cylinder and fountain bowl.

10. In an intaglio printing press, a printing couple including either of two printing cylinders of different diameters but having shafts of the same diameter, a frame, slide blocks mounted on said frame and providing bearings for the shaft of either printing cylinder, means for adjusting the bearings vertically between two positions so related that either of the printing cylinders may be adjusted to the same printing level, a fountain bowl, means for adjusting the fountain bowl vertically, a housing for the printing cylinder and fountain bowl fitted between said blocks, said housing having end walls each formed with an opening to clear the cylinder shaft in either position of the bearings, and means adapted to fit about said shaft and close said openings.

11. In an intaglio printing press, a printing couple including either of two printing cylinders of different diameters but having shafts of the

same diameter, a frame, slide blocks mounted on said frame and providing bearings for either printing cylinder shaft, means for adjusting the bearings vertically between two positions so related that each of the printing cylinders may be adjusted to the same printing level, a fountain bowl, means for adjusting the fountain bowl vertically, and a housing for the printing cylinder and fountain bowl fitted between said blocks, each end wall of the housing having an opening therein centered with respect to said positions and adapted to clear the shafts in each bearing position, the end wall of each opening being formed with a pair of half-round recesses, one for each shaft, and a sliding door for each housing opening, said door being formed with an end extension to close the upper one of said recesses and a half-round end recess to match the lower recess of said pair and form therewith a complete circular shaft opening, said door being reversible to close said lower recess and form a shaft opening with said upper recess.

12. In an intaglio printing press, a printing couple, a frame, slide blocks mounted on said frame and providing bearings for the printing cylinder shaft, means for adjusting the bearings vertically, a fountain bowl for the printing cylinder, means for adjusting the fountain bowl vertically, and a housing for the printing cylinder and fountain bowl fitted between said blocks, each end wall of the housing having an opening therein centered with respect to said positions and adapted to clear the shafts in each bearing position, the end wall of each opening being formed with a pair of half-round recesses, one for each shaft, and a sliding door for each housing opening, said door being formed with an end extension to close the upper one of said recesses and a half-round end recess to match the lower recess of said pair and form therewith a complete circular shaft opening, said door being reversible to close said lower recess and form a shaft opening with said upper recess.

13. In an intaglio printing press, a printing couple, a frame, slide blocks mounted on said frame and providing bearings for the shaft of the printing cylinder, means for adjusting the bearings vertically, a fountain bowl for the printing cylinder, means for adjusting the fountain bowl vertically, a housing for the printing cylinder and fountain bowl fitted between said blocks, said housing having end walls each formed with an opening to clear the cylinder shaft in any position of the bearings, and means adapted to fit about said shaft and close said openings.

HANS C. JORDHOY.
